FIG. 3.

FIG. 4.

INVENTOR,
JOHN F. PLATTE.
BY Martin P. Smith, ATTY.

UNITED STATES PATENT OFFICE

1,984,807

AWNING

John F. Platte, South Gate, Calif.

Application March 23, 1934, Serial No. 717,009

3 Claims. (Cl. 156—16)

My invention relates to an awning or porch curtain and has for its principal object, the provision of a relatively simple, strong and durable awning or curtain composed of slats that are 5 connected by flexible members such as chains in order that the completed structure may have a certain degree of flexibility when installed for use and which flexible construction enables the awning or curtain to be rolled up so as to occupy 10 comparatively little space when packed for storage or transportation.

A further object of my invention is, to provide improved means for securely fastening the links of the chains to the slats.

15 With the foregoing and other objects in view my invention consists in certain novel features of construction and arrangements of parts that will be hereinafter more fully described and claimed and illustrated in the accompanying 20 drawing in which:

Fig. 1 is an end elevational view of an awning constructed in accordance with my invention and mounted for use on suitable supports.

Fig. 2 is an enlarged sectional view of a portion 25 of the awning and showing one of the supports therefor.

Fig. 3 is a view looking against the underside of a portion of the awning and showing one of the flexible members that connects the slats.

30 Fig. 4 is a cross section taken on the line 4—4 of Fig. 3.

Referring by numerals to the accompanying drawing which illustrates a preferred embodiment of my invention, 10, 10 designate slats 35 preferably formed of wood and substantially rectangular in cross section, which slats are arranged parallel with each other and with their adjacent edges spaced a slight distance apart.

40 Applied to the under or inner faces of the slats and disposed at right angles thereto, are suitably spaced chains 11, preferably of the type employed in window sash counter balancing means. These chains, which are readily 45 obtainable in the open market, are composed of links bent double with the end portions of each link having coinciding openings that receive the bent end of the next adjacent link.

In order to secure the chains to the slats, nails 50 12 are driven through the slats so that the points of said nails project as illustrated by dotted lines in Fig. 4.

The chains are now applied to the under or rear faces of the slats so that the projecting 55 portions of the nails extend through the looped

portions of certain of the chain links, after which the portions of the rails that project through the loops of the chains are bent at right angles. The chains which are standing on edge against the slats, are now given a quarter turn so as to lie flat against the inner or under faces of the slats and such action accompanied by sufficient pressure, forces the points of the nails into the slats on the opposite side from those portions of the nails that extend entirely through the 10 slat (see Fig. 4).

Thus in effect the attaching nails function as staples to secure the chains to the slats within an intermediate portion of each nail passing through one of the chain links and all of the 15 links lying flat against the inner or under sides of the slats.

To mount the slatted structure for use as an awning as illustrated in Fig. 1, one end of the slatted structure is secured in any suitable manner, preferably by means of screw eyes 13, to a cleat or fixed support 14, and the outer portion 20 of the awning is positioned upon a suitable horizontally disposed support.

In the present instance I have shown the support for the outer portion of the awning in the form of a metal tube or pipe 15 and the end portions of this supporting member are connected preferably by means of turn buckles, such as 16, to the upper portions of upright members 30 or standards 17.

25 In order to secure the outer portion to the supporting rail 15, wires such as 18 are passed beneath the supporting rail and the ends of said wires are twisted through links of the chains 35 that connect the slats.

The use of nails in securing the chains to the slats and the bending of the projecting ends of the nails so that the same extend 40 through the chain links and with the points of the nails driven into the slats, provides simple, efficient and inexpensive means for securely connecting the chains to the slats and a flexible structure is produced that may be used as an awning, a blind, porch curtain or the like.

45 Thus it will be seen that I have provided a flexible awning or curtain that is relatively simple in construction, inexpensive of manufacture and very effective in performing the functions for which it is intended.

50 It will be understood that minor changes in the size, form and construction of the various parts of my improved awning may be made and substituted for those herein shown and described without departing from the spirit of my invention.

tion, the scope of which is set forth in the appended claims.

I claim as my invention:

- 5 1. An awning, comprising a plurality of parallel slats, chains arranged on the under or inner faces of said slats and extending at right angles thereto, nails severally passing through said slats with the projecting portion of each nail extending through a link of said chains and the point of each nail extending into the associated slat at the side of the associated chain.
- 10 2. An awning, comprising a series of parallel slats, chains having flat links arranged on the under or inner faces of said slats, nails severally passing through said slats, portions of which
- 15

nails are bent at right angles and severally extend through the links of said chains and the points of which nails are rebent and extend into the slats on the opposite sides of the associated links from the main body portions of said nails.

- 5 3. An awning, comprising a series of parallel slats, chains secured to the under or inner faces of said slats, one end of said awning adapted to be fastened to a fixed support the other end portion of the awning adapted to be supported on a rail and fastening means passing around said rail and secured to said chains.

JOHN F. PLATTE. 15
